UNITED STATES PATENT OFFICE.

ALBERT H. TRAGESER AND LOUIS HASSINGER, OF NEW YORK, N. Y.

STAND BOILER AND WATER HEATER.

Application filed September 15, 1923. Serial No. 662,965.

To all whom it may concern:

Be it known that we, ALBERT H. TRAGESER and LOUIS HASSINGER, both citizens of the United States, and residents of the city of 5 New York, borough of Manhattan, in the county and State of New York, have invented a new and Improved Stand Boiler and Water Heater, of which the following is a full, clear, and exact description.

10 The present invention relates to new and useful improvements in stand boilers and it pertains more particularly to a stand boiler of the type having a burner associated therewith for the purpose of heating water contained in the boiler.

15 It is one of the primary objects of the invention to construct a stand boiler in such a manner that water may be rapidly heated.

20 It is a further object of the invention to provide circulating means whereby the water heated will be delivered to the upper portion of the boiler out of contact with the water of lower temperature contained in the boiler.

25 It is a further object of the invention to provide a water heating chamber closely associated with the burner, which water heating chamber is insulated from the water of lower temperature within the boiler, thus 30 heating the water in the water-heating chamber in a more efficient manner.

35 It is a further object of the invention to protect that portion of the circulating system which delivers the heated water to the upper end of the boiler from the action of the water of lower temperature contained in the boiler by means of a suitable insulation.

40 With the above and other objects in view, reference is had to the accompanying drawings, in which the figure is a longitudinal sectional view of a stand boiler constructed in accordance with the present invention.

45 Referring more particularly to the drawings, the boiler is designated by the reference numeral 5, and is carried by the usual stand or support 6. Leading into the upper end of the boiler is a pipe 7, which supplies water thereto, and leading from the side of the boiler is a pipe 8, by means of which the boiler is connected to the water back of a range or other suitable heating device, all of which is common construction in boilers 50 of this type.

55 The reference numeral 9 designates a wall, and said wall is supported in spaced relation to the bottom end wall 10 of the stand

boiler 5. This wall is formed with a flange 11, and said flange is provided with a plurality of openings 12, by means of which the water from the boiler has entrance to the 60 space between the wall 9 and the bottom end wall 10 of the boiler. Leading upwardly from the wall 9 there is a pipe 13, and such pipe has its upper end terminating at a point close to the top end wall of the 65 boiler 5, as shown at 14.

Spaced with respect to the wall 9, there is a wall 15 secured to the wall 9 by welding or other suitable means at the point 16. This construction provides an intervening space 70 which is filled with asbestos or other suitable heat-insulating material 17. Projecting upwardly from this wall 15, there is a tubular member 18, such member being of a diameter greater than the diameter of the pipe 13, 75 and this construction provides an intervening space which is filled with asbestos or other suitable material 19. The tubular member 18 is secured to the upper end 14 of the circulating pipe 13, as shown at 20. 80

The reference character 21 designates a burner which may be of the gas or liquid fuel type, and said burner is placed in juxtaposition to the bottom end wall 10 of the stand boiler 5 in such a manner that its 85 flame will heat the water in the space between the wall 9 and the bottom end wall 10 of the boiler. The water in this space being heated circulates upwardly through the pipe 13 and is discharged in the upper end of the 90 boiler, and is displaced by the water of lower temperature within the boiler 5, and which is fed to the boiler 5 by means of the pipe 7.

Due to the natural circulation within devices of this character, the water of lowest 95 temperature is at the bottom of the boiler.

By providing the asbestos filled space between the wall 15 and the wall 9, the water within the heating chamber is protected from the cooling effect of the water of lower 100 temperature in the lower portion of the boiler and the heating operation of the water within the heating chamber is consequently more rapid than it would be were it not for the heat insulating material. Furthermore, by providing the heat insulating material 19 in the space between the circulating pipe 13 and the tubular member 18, the heated water as it circulates upwardly 105 through the pipe 13 is protected from the 110 cooling action of the water of lower temperature surrounding said circulating pipe 13.

From the foregoing it is apparent that the present invention provides a new and improved form of water-heating boilers, which, owing to its construction, provides for quicker heating of the water and a protection against rapid cooling of the heated water during its circulation through the cooled water contained within the boiler.

While in the present instance the invention is shown as a permanent part of a stand boiler, it is obvious that the same may be made as a removable unit and attached to stand boilers or stand boiler bottoms without departing from the spirit of the invention.

What is claimed is:

An attachment for stand boilers comprising an inverted dome-shaped member mounted upon the bottom wall of the boiler with

its side walls provided with openings and spaced with respect to the side walls of the boiler, a circulating pipe projecting upwardly from said inverted dome-shaped member, a wall supported upon the top of said dome-shaped member and in spaced relation thereto to provide an intervening chamber, a tubular extension projecting from said wall and surrounding said circulating pipe, the tubular extension being secured to the circulating pipe at the upper end thereof, the space between the circulating pipe and the tubular extension and the wall and the inverted dome-shaped member being filled with a heat-insulating material.

ALBERT H. TRAGESER.
LOUIS HASSINGER.
